UNITED STATES PATENT OFFICE.

BERNARD A. RICHARDS, OF CLEVELAND, OHIO.

BLOCK-MOLDING MACHINE.

1,355,619.

Specification of Letters Patent. Patented Oct. 12, 1920.

Application filed November 24, 1919. Serial No. 340,285.

To all whom it may concern:

Be it known that I, BERNARD A. RICHARDS, a citizen of the United States, residing at Cleveland, in the county of Cuyahoga and State of Ohio, have invented a certain new and useful Improvement in Block-Molding Machines, of which the following is a full, clear, and exact description, reference being had to the accompanying drawings.

10 This invention relates to multiple concrete block molding machines and has for its objects to provide a machine of this character which shall be readily adjustable whereby blocks of different sizes may be readily formed; to provide a machine of large capacity, of compact form that is simple in construction and easy to operate; while further objects and advantages will appear as the description proceeds.

20 In the accompanying drawings wherein I have shown an illustrative embodiment of my invention, Figure 1 is a fragmentary side elevation of the machine; Fig. 2 is a front end view thereof; Fig. 3 is a top plan view of the part shown in Fig. 1; and Fig. 4 is a detail perspective view of the molds.

Describing the various parts by reference numerals, 1 indicates the supporting cross frames which are spaced apart and connected together by the side members 2. A series of rollers 3 are journaled in suitable bearings in the side members 2 and support the movable rectangular frame 4. The side plates 5 are hinged as at 7 to the rectangular frame 4 and are held in upright position by any suitable means as by the buttons 8 which engage the arcuate cams 9 and bind the side plates and mold parts tightly together. Each of the side members is provided with a series of spaced grooves as indicated at 10 which receive partition plates 11 which determine the size of the blocks to be formed, and in this case I have shown the side plates grooved to form three sizes of blocks as for example, eight, ten and twelve inch blocks although it is understood that any size or any number of sizes could be made by simply spacing the grooves to the desired distances. The sides 5 are each provided 50 with a series of holes 12 so that the end

core 13 may be positioned centrally of each size block and each core is provided with a stud bolt which projects through a hole 12 and has threaded therein a nut 14 to clamp the core in position. The top of one of the 55 side plates 5, preferably that side on which the operator stands, is provided with a series of holes 18 in transverse alinement with each pair of grooves and these holes are adapted to receive removable pins 20, 60 the purpose of which will be explained later. Each mold is provided with a pallet 16 which rests on the rails 17-17 extending from end to end on the frame 4 and these rails are preferably so positioned, that a 65 small space is left under each end of the pallet to insert the fingers for lifting the finished blocks from the molds.

The rectangular frame and mold are guided during longitudinal movement between the rollers 21 and 22 mounted in the brackets 24 which rise from opposite points on the supporting cross frames 1, the rollers 21 bearing against the rectangular frame 4 and the rollers 22 against the side plates 5. 70 A suitable spring pressed stop lever 23 is mounted on the top of a forward bracket so as to contact with a pin 20 and thereby aline each mold under the tamping and filling apparatus represented at 25 and 26, respectively. The frame 4 is provided on its under side, preferably along its longitudinal axis, with a rack 27 which has a gear 28 carried by the shaft 29 meshing therewith. The shaft 29 is journaled in suitable 75 bearings in the side members 2 and on one end there is secured a ratchet wheel 30 while a lever 31 is loosely mounted on the shaft and is provided with a pawl 32 engageable with the ratchet wheel to rotate gear 28 and 80 thereby advance the mold.

In operation the rectangular frame and molds are fed under the filling apparatus 26 where they are filled with concrete and are advanced by the hand lever 31 until the 95 first of the pins 20 engage the stop lever 23 when the tamping apparatus 25 is operated to tamp the first mold. When the tamping operation is completed, the stop lever 23 is depressed and the hand lever 100

operated to bring the next mold into position for tamping which is indicated by the next pin 20 engaging stop lever 23. After a complete set of molds are filled and tamped 5 they may be slid onto a suitable conveyer (not shown) and carried thereby to a convenient place and when it is desired to remove the blocks, the buttons 8 are lowered to allow the side plates 5 to drop which permits access to each mold and the concrete blocks may be easily removed by lifting each pallet therefrom.

Having thus described my invention, what I claim is:—

15 1. In a molding machine, the combination of a supporting frame, a rectangular frame adapted to slide in said supporting frame, side members hinged to said rectangular frame, means for holding said members upright, a plurality of partition elements arranged in adjustable relationship between 20 said members, and means for advancing said rectangular frame step by step along said supporting frame.

25 2. In a molding machine, the combination of a supporting frame, a rectangular frame adapted to slide in said supporting frame, a pair of longitudinal rails mounted on said rectangular frame adapted to receive a 30 pallet, side members hinged to said rectangular frame, a plurality of partition elements arranged in adjustable relationship between said members, and means for advancing said rectangular frame step by step 35 along said supporting frame.

35 3. In a molding machine, the combination of a supporting frame, a rectangular frame adapted to slide in said supporting frame, side members hingedly connected to said 40 rectangular frame, a plurality of partition elements arranged between said members, and cores carried by said side members centrally of said partition elements, a rack mounted longitudinally on said rectangular frame, a gear carried by said supporting frame meshing with said rack, and means for 45 rotating said gear to move said rectangular frame along said supporting frame.

45 4. In a molding machine, the combination of a plurality of transverse supporting elements, side elements connecting said transverse elements in alinement, a pair of brackets provided with a plurality of rollers arranged in opposed relationship on each of 50 said transverse elements, a rectangular frame provided with a plurality of molds, and means for sliding said frame and said molds between said rollers.

5. In a molding machine, the combination 60 of a supporting frame, a rectangular frame adapted to slide in said supporting frame, said members hinged to said rectangular frame, means for holding said members upright, a plurality of partition elements arranged between said members, and means 65

for advancing said rectangular frame step by step along said supporting frame.

6. In a molding machine, the combination of a supporting frame, a rectangular frame adapted to slide in said supporting frame, 70 a pair of longitudinal rails mounted on said rectangular frame adapted to receive a pallet, side members hinged to said rectangular frame, a plurality of partition elements arranged in adjustable relationship between 75 said members and adapted to rest on said rails and means for advancing said rectangular frame step by step along said supporting frame.

7. In a molding machine, the combination 80 of a supporting frame, a rectangular frame adapted to slide in said supporting frame, side members hingedly connected to said rectangular frame, a plurality of partition elements arranged in adjustable relationship 85 between said members, end cores adjustable in said side members centrally of said partition elements, a rack mounted longitudinally on said rectangular frame, a gear carried by said supporting frame meshing with said rack and means for rotating said gear to move said rectangular frame along said supporting frame.

8. In a molding machine, the combination of a guiding frame, a molding frame having collapsible sides and partition elements held in spaced relation by said sides, and means for moving said molding frame along 95 said guiding frame whereby said parts are held in operative position by said guiding frame.

9. In a molding machine, the combination of a guiding frame, a molding frame having a plurality of molds therein, a stop member carried by said guiding frame, a plurality of cooperating stop members carried by said molding frame, and means for bringing each of said last mentioned members successively into engagement with said first mentioned member.

10. In a molding machine, the combination of a guiding frame, a molding frame having a plurality of molds therein, a stop member carried by said guiding frame, a plurality of pins disposed along one side 110 of said molding frame for successive engagement with said stop member, and means for moving said molding frame along said guiding frame.

11. In a molding machine, the combination of a guiding frame, a molding frame having a plurality of molds therein, a stop member carried by said guiding frame, a removable pin corresponding to each mold carried by said molding frame, and means 120 for moving said molding frame along said guiding frame to bring the pins successively into engagement with said stop member and stop each mold in a predetermined position.

12. In a molding machine, the combina- 13

tion of a guiding frame, a molding frame having a plurality of molds therein, a stop member carried by said guiding frame, a second stop member corresponding to each 5 mold carried by said molding frame, said second member being adapted to engage said first member upon movement of said

molding frame along said guiding frame and means for disengaging one of said stop members from the other.

10

In testimony whereof, I hereunto affix my signature.

BERNARD A. RICHARDS.
